ATTORNEY

UNITED STATES PATENT OFFICE.

MAX NEUMERKEL, OF MADISON, CONNECTICUT.

ADJUSTABLE WRENCH.

Application filed April 11, 1927. Serial No. 182,685.

This invention relates to wrenches, particularly adjustable or monkey wrenches and has for its principal object to provide a construction which will be durable, effective and which will permit fine adjustment of the jaws of the wrench for different sizes of nuts or other jaws for which it is to be used.

With this and other objects in view my invention consists in the novel construction, combination and arrangement of parts as will be hereinafter more fully described and defined in the appended claims.

In the accompanying drawing in which similar reference characters denote corresponding parts Fig. 1 is an elevation of my new wrench of which a part is broken away to show certain details of construction; Fig. 2 is an enlarged cross section on line 2—2 of Fig. 1; Fig. 3 is an enlarged cross section on line 3—3 of Fig. 1; Fig. 4 is a view similar to that of Fig. 1 of the lower part of the wrench also partly broken away showing the movable jaw released for coarse adjustment; Fig. 5 is an elevation of a modified construction of a sectional wrench of which one section is removed to show details of construction; Fig. 6 is a front view of the assembled wrench and Fig. 7 is a cross section on line 7—7 of Fig. 5.

Referring to the drawing more specifically, and first the construction shown in Figs. 1—4 inclusive, the wrench comprises a bar or shank 10 formed at one end with an integral stationary jaw 11 projecting at a right angle to said shank. The upper part or half of the shank 10 has flat side surfaces while the lower part or half thereof is of cylindrical shape as at 10'. The front edge of the shank 10 is provided with a longitudinal groove 10² which extends from the stationary jaw 11 to an intermediate point of the cylindrical part 10' of the shank. Slidably supported and guided in the groove 10² by means of a U-shaped member or brace 12^a is a movable jaw 12 which is formed with an extension 12' slidably borne in said groove 10² and whose forward edge has fine worm thread 12². Rotatively mounted on said cylindrical portion 10' of the shank is an externally serrated or ribbed sleeve 13 of brass or the like to the inner face of which is suitably fixed a second sleeve 14 of steel provided with an internal fine thread 14'. A part of

this internal thread is cut away as at 14², the cut away portion being of a width about equal to or slightly larger than the thickness of the rack 12². When the sleeve 13 is given a certain turn the thread 14' is capable of being brought into mesh with the rack 12² so as to positively move the movable jaw 12 toward or away from the stationary jaw 11 for fine adjustment of the former. When the sleeve 13 is given a certain other turn the cut away portion 14² of the thread 14' is brought into register with the rack 12² and consequently the movable jaw 12 is released to slide freely in the groove 10² for coarse adjustment. The sleeve 13 is freely rotatable on the cylindrical portion 10' of the shank and is held from slipping off the latter by a head piece 10³ provided at the opposite end of the shank. The rotary motion of the sleeve 13 on the cylindrical part 10' is limited by a stop pin 15 which cooperates with a shoulder 13' formed by cutting away a part 13² of the lower end of the sleeve 13. When using the wrench the sleeve 13 is given a turn in a certain direction so as to bring the cut away part 14² of the thread 14' in register with the rack 12². As a result thereof the movable jaw 12 can be freely moved toward and away from the stationary jaw 11 permitting a rough adjustment thereof relative to the stationary jaw. Upon this rough adjustment the sleeve 13 is turned in the opposite direction to bring the thread 14' into mesh with the rack 12², thereby positively effecting a fine adjustment of said movable jaw and at the same time locking the latter against retrograde movement.

In the modification shown in Figs. 5 to 7 the shank 16 of the wrench is composed of two longitudinal and substantially uniform sections 16^a, 16^b which when assembled are adapted to be riveted or screwed together as at 16^c. Each section is formed at its upper end with an integral projection 17 which when the parts are assembled constitute the stationary jaw of the wrench. The upper part of each section immediately below the stationary jaw 17 is slanting forwardly and formed with a longitudinally extending shallow and flat groove 16' which when the two sections are assembled form a groove of rectangular cross section. Each section is also provided with a groove 16² of semi-cylindrical cross section extending

longitudinally from the lower end of the groove 16' to the bottom end of the wrench and which when the sections are assembled form a cylindrical bearing for the purpose hereinafter described.

Freely movable and guided in the rectangular groove 16' is the movable jaw 18. This jaw is formed with a forwardly slanting bar like extension 18' which is slidably borne in said groove 16' and which is guided and held in said groove by a rib 16^a provided in and extending longitudinally through the slanting portion of one of the sections as 16^a and engaging a guide groove 18². The rear edge of the extension 18' of the movable jaw 18 is formed with worm thread 18³ extending through the entire length thereof. Rotatively mounted in the cylindrical bearing 16² is a spindle 19 the upper end of which projects into the groove 16' and is formed to a conical worm gear 23 capable of meshing with the threaded edge 18³ of the extension 18' of the movable jaw. A part of this worm gear is sufficiently cut away as at 23' so that when by turning the spindle 19 it is positioned opposite the toothed edge 18³ the movable jaw 18 will be released and can be freely moved toward or away from the stationary jaw 17 for coarse adjustment. When the spindle is given a certain other turn its toothed portion will engage the edge 18³ and move the movable jaw 18 positively either toward or away from the stationary jaw 17 and effect the desired fine adjustment of the movable jaw. The rotation of the spindle 19 is effected by an externally threaded sleeve or cap 20 which works on the lower externally threaded cylindrical end 16^e of the shank 16 and which by screw bolts 21 is coupled to spindle 19. For limiting the rotation of the latter I use a stop pin 22 fixed in the lower end of the spindle and which cooperates with a shoulder 20' formed by cutting away the lower part of the shank as at 20².

Provided in the shank 16 is a member 24 which is pivotally secured in a groove thereof (not shown) as at 24' and which is provided with a toothed projection 24² adapted to extend outwardly from the stem and capable of meshing with the toothed edge 18³ of the extension 18'. This projection 24² is provided with a cross pin or the like 25 projecting through slots 16³ of the shank sections and carrying knobs 25' whereby the member 24 may be manipulated by hand from the outside so as to disengage the same from the edge 18³. A plate spring 26 tends to hold the toothed projection 24² constantly in engagement with the edge 18³. The projection 24² acts as a safety lock holding the movable jaw 18 locked in adjusted position.

In use the spindle 19 by a single turn of

the sleeve or cap 20 is positioned so that the broken away part 23' of the conical gear 23 registers with the edge 18³ of the extension 18' thereof. By pressing the member or part 24 through the medium of the knobs 25' rearwardly the toothed projection 24² becomes disengaged from the edge 18³ as a result of which the movable jaw is released and free to be moved in the stem 16 for coarse adjustment thereof. After such coarse adjustment when the sleeve 20 is given a turn in the opposite direction the spindle 19 and its threaded cone is brought into mesh with the edge 18³ whereby the movable jaw is positively moved toward or away from the stationary jaw for a finer adjustment. The auxiliary lock 24² prevents retrograde movement.

The front edge of the movable jaw 18 may be roughened or serrated as at 18⁴ so as to facilitate the coarse adjustment thereof by hand.

It is understood that various other modifications may be made in the device without departing from the principle of my invention and I therefore do not wish to restrict myself to the details described and shown.

What I claim is:

1. In an adjustable wrench, a shank formed with a stationary jaw, a second jaw freely movable in said shank and formed with a threaded extension, a rotary spindle in said shank provided with means for longitudinal displacement thereof and having a threaded portion of which a part is broken out, said threaded portion being capable when given a certain turn of coming into mesh with said threaded extension and of positively moving said movable jaw to effect fine adjustment, and when given a certain other turn to come with its broken out portion into register with said threaded extension releasing said movable jaw to effect coarse adjustment.

2. In an adjustable wrench, a shank formed with a stationary jaw, a second jaw freely movable in said shank and formed with a threaded extension, a rotary spindle in said shank provided with means for longitudinal displacement thereof and having a threaded portion of which a part is broken out, said threaded portion being capable when given a certain turn of coming into mesh with said threaded extension and of positively moving said jaw to effect fine adjustment, and when given a certain other turn to come with its broken out portion into register with said threaded extension releasing said movable jaw to effect coarse adjustment, and means for limiting the turning movement of said spindle.

3. In an adjustable wrench, a shank formed with a stationary jaw, a second jaw freely movable in said shank and formed with a threaded extension, a rotary spindle

in said shank provided with means for longitudinal displacement thereof and having a threaded portion of which a part is broken out, said threaded portion being capable of being brought into mesh with said threaded extension to effect fine adjustment, and of being brought with its broken out portion into register with said threaded extension to release said movable jaw for coarse adjustment and an auxiliary lock to hold said movable jaw in adjusted position.

4. In an adjustable wrench, a grooved shank formed with a stationary jaw, a second jaw formed with a threaded extension and freely movable and guided in the groove of said shank, a spindle rotatively mounted in said shank provided with means for longitudinal displacement thereof and formed with a worm gear of which a part is broken out and which is capable of meshing with said threaded extension to positively move said movable jaw and effect fine adjustment thereof and when brought with its broken out part into register with said threaded extension to release said movable jaw for coarse adjustment, means on said shank for turning said spindle and means for limiting the turning movement of said spindle.

5. In an adjustable wrench, a grooved shank formed with a stationary jaw, a second jaw formed with a threaded extension and freely movable and guided in the groove of said shank, a spindle rotatively mounted in said shank provided with means for longitudinal displacement thereof and formed with a threaded extension of which a part is broken out and which is capable of operatively engaging and positively moving said movable jaw toward and away from said stationary jaw and of disengaging the same to release said movable jaw, means on said shank for turning said spindle, means for limiting the turning movement of said spindle and an auxiliary lock for locking said movable jaw in adjusted position.

6. In an adjustable wrench, a grooved shank formed with a stationary jaw, a second jaw formed with a threaded extension and freely movable and guided in the groove of said shank, a spindle rotatively mounted in said shank provided with means for longitudinal displacement thereof and formed with a threaded extension of which a part is broken out and which is capable of operatively engaging and positively moving said

movable jaw toward and away from said stationary jaw and of disengaging the same to release said movable jaw, means on said shank for turning said spindle, means for limiting the turning movement of said spindle and a manually controlled locking means for locking said movable jaw in adjusted position.

7. In an adjustable wrench, a grooved shank formed with a stationary jaw, a second jaw formed with a threaded extension and freely movable and guided in the groove of said shank, a spindle rotatively mounted in said shank provided with means for longitudinal displacement thereof and formed with a threaded extension of which a part is broken out and which is capable of operatively engaging and positively moving said movable jaw toward and away from said stationary jaw and of disengaging the same to release said movable jaw, means on said shank for turning said spindle, means for limiting the turning movement of said spindle, and a spring actuated manually controlled means cooperating with said threaded extension for locking said movable jaw in position.

8. In an adjustable wrench, a shank formed at one end with a stationary jaw and at its other end with a threaded portion, a second jaw freely movable in said shank and formed with a threaded extension, a rotary spindle mounted in said shank, provided at one end with a threaded portion having a part thereof broken out and rigidly engaging at its lower end a sleeve, said sleeve adapted to engage said first named threaded portion, whereby, when said sleeve is rotated in certain direction said spindle also rotates and the threaded portion thereon comes into mesh with said threaded extension and said sleeve screws onto said first named threaded portion causing longitudinal displacement of said spindle, the combined action of said meshing and said longitudinal feeding effecting fine adjustment of said movable jaw, and when said spindle is rotated in a certain other direction, said broken out portion will register with said threaded extension and release said last named jaw for coarse adjustment thereof.

In testimony whereof I affix my signature.

MAX NEUMERKEL.
